INVENTOR

EDWARD P. BEACH,
BY Brakeman, ATTY'S.

UNITED STATES PATENT OFFICE.

EDWARD P. BEACH, OF NEWARK, NEW JERSEY.

DESIGN FOR A BROOCH.

SPECIFICATION forming part of Design No. 20,009, dated July 15, 1890.

Application filed May 3, 1890. Serial No. 350,526. Term of patent 3½ years.

To all whom it may concern:

Be it known that I, EDWARD P. BEACH, a citizen of the United States, residing at Newark, in the county of Essex and State of New Jersey, have invented and produced a new and original Design for Brooches and Similar Articles of Jewelry; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

15 Said drawing represents a face or plan view of my design for a brooch and similar articles, such as a scarf pin or button. This view is deemed sufficient to fully illustrate said design, the leading feature of which consists in 20 the configuration or form of the article, which comprises the representation of two yoke-like convolutions reversed in relation to each other in the conventional form of an ellipse contracted at its transverse diameter, with the 25 arms or ends of one yoke intertwined or wrapped around the arms of the other yoke, and having a single blunt projection arising from one end of each of the intertwined portions at each end of the brooch, as will be 30 hereinafter set forth and claimed.

In said drawing, *a* and *b* indicate two ornamenteally-engraved convolutions or curvatures intersecting and intertwining with one another in a peculiar manner or form, to wit: each part presents a yoke-like appearance reversed in relation to the other, with the arms of each yoke twisted with those of the other, and with the extremity of one arm of one yoke exposed at one end of one of the curvatures and presenting the appearance of being cut off diagonally, and the extremity of the opposite arm of the other yoke exposed at the opposite end of the other curvature and presenting the appearance of being cut off diagonally, the ends of the other arms of each of the yokes disappearing under the curvatures at each end of the brooch. Gems may be set at the center, if desired.

35 40 45 50
What I claim is—

The design for a brooch or similar article, substantially as herein shown and described.

In testimony that I claim the foregoing I have hereunto set my hand this 1st day of May, 1890.

EDWARD P. BEACH.
